UNITED STATES PATENT OFFICE.

FREDERICK C. MERCUR, OF HENRYETTA, OKLAHOMA.

VEHICLE-TIRE

1,249,985.

Specification of Letters Patent. Patented Dec. 11, 1917.

Application filed March 2, 1917. Serial No. 152,064.

To all whom it may concern:

Be it known that I, FREDERICK C. MERCUR, a citizen of the United States, residing at Henryetta, in the county of Okmulgee and 5 State of Oklahoma, have invented new and useful Improvements in Vehicle - Tires, of which the following is a specification.

This invention relates to improvements in the construction of vehicle tires.

10 In carrying out my invention it is my purpose to produce a spring tire comprising an endless series of spring bands having their inner and outer sides thickened and the said thickened sides being provided with continuous 15 depressions and to arrange within each of the said depressions a flat ring having transverse ribs disposed to engage between the bands to sustain the said bands in non-contacting relation and at the same time 20 serve to connect the bands, the reduced thickness of the transverse sides of the bands being adapted to afford the desired resiliency for the tire.

With the above and other objects in view 25 the improvement resides in the construction, combination and arrangement of parts set forth in the following specification and falling within the scope of the appended claims.

In the drawings:

30 Fig. 1 is a side elevation of the improvement,

Fig. 2 is a sectional view approximately on the line 2—2 of Fig. 1, taken upon an enlarged scale,

35 Fig. 3 is a longitudinal sectional view taken approximately on the line 3—3 of Fig. 2,

Fig. 4 is a perspective view of one of the spring bands,

40 Fig. 5 is a detail perspective view of a portion of one of the flat spring members, and

Fig. 6 is a detail view illustrating the improvement provided with a tread member.

45 The improvement contemplates the employment of an endless series of round metallic spring bands 2. Each of the bands 2 is gradually increased in thickness from its sides to its inner and to its outer edge, as

50 indicated by the numerals 3—3, and the maximum thickness of each of said bands is at diametrically opposite points. Each of the thickened portions 3—3 is formed with a transverse depression or channel indicated for distinction by the numerals 4 and 5 re-

spectively, the depression 4 being upon the outer surface of the band and the depression 5 being arranged upon the inner surface of the said band. The bands 2 are arranged in an endless series, as clearly illustrated in 60 Fig. 1 of the drawings, and the depressions 4 and 5 are adapted to receive flat ring members 6 and 7 respectively, each of the said rings having its inner face provided with transverse ribs 8 and 9 respectively, the said 65 ribs being disposed to engage between the bands and to sustain said bands in non-contacting relation. The space between the confronting bands is comparatively slight and may, if desired, be covered by the casing of 70 a pneumatic tire (not shown), or in any other suitable manner. The rings 6 and 7 each may comprise a split member and may have their ends drawn together in any desired or preferred manner so as to tightly 75 force the bands against the ribs of the said rings, and by reference to the said drawings it will be noted that the rings are of a thickness approximately corresponding with the depth of the depressions 4 and 5 and are 80 also of a width corresponding with the width of the said depressions, and from a construction as above described it will be noted that the recesses provide pockets for the rings to properly retain the rings upon 85 the bands, and the bands in proper spaced relation to each other, while the reduced sides of said bands provide for the necessary yielding or resiliency of the tire. It is to be understood that, if desired, the tire may 90 be arranged in an outer casing, but, as illustrated. In Fig. 6 of the drawings, the outer ring member, indicated by the character 10, may provide a tread or bearing surface for the tire, the said ring having its inner face 95 concaved to engage with the thickened portions of the bands 2, and its said inner face also provided with a centrally disposed continuous flange 11 to be received in the depressions 4 of the said bands 2, the said 100 flange being, of course, provided with transverse ribs, similar to the ribs 8 and 9 upon the members 6 and 7.

From the above description, taken in connection with the accompanying drawings 105 the simplicity of the device, as well as the advantages thereof will, it is thought, be perfectly apparent to those skilled in the art to which such invention appertains without further detailed description.

Having thus described the invention, what I claim is:

1. A spring tire comprising an endless series of continuous bands which have diametrically opposite thickened portions and their said thickened portions being formed with registering depressions, ring members for the bands designed to be received in the said depressions, said ring members having 10 transverse ribs disposed to engage between the bands and to sustain said bands in non-contacting relation.
2. A spring tire comprising an endless series of continuous bands, said bands having diametrically opposite thickened portions, the said thickened portions upon the 15

outer faces of the bands having registering substantially rectangular depressions and the thickened portions upon the inner faces of the bands having similar registering substantially rectangular depressed portions, a pair of ring members for the bands designed to be received one in the inner and one in the outer series of depressions and to contact with the inner and side walls provided by the depressions, and each of said ring members having transverse ribs disposed to engage between the bands and to sustain the bands in non-contacting relation. 20 25

In testimony whereof I affix my signature. 30

FREDERICK C. MERCUR.

Copies of this patent may be obtained for five cents each, by addressing the "Commissioner of Patents, Washington, D. C."
